THEODOR O. JORGENSEN ^{Inventor}

By Richard B. Deven

Attorney

UNITED STATES PATENT OFFICE.

THEODOR O. JORGENSEN, OF BETHLEHEM, PENNSYLVANIA.

SIGN.

1,357,457.

Specification of Letters Patent.

Patented Nov. 2, 1920.

Application filed January 30, 1920. Serial No. 385,151.

To all whom it may concern:

Be it known that I, THEODOR O. JORGENSEN, a citizen of Denmark, residing at Bethlehem, in the county of Lehigh and State of Pennsylvania, have invented certain new and useful Improvements in Signs, of which the following is a specification.

This invention relates to signs and more especially to changeable signs which are capable of forming every letter of the alphabet.

The principal object of the invention is to produce simple and efficient means for quickly changing to the desired letter.

Another object of the invention is to provide means whereby the sign may be normally and automatically changed to a blank.

In order to carry out the above and other objects, I provide a sign board of rectangular construction having a plurality of shutters hingedly mounted upon one surface of the board so as to outline the various elements of all the letters of the alphabet, one face of the shutters being colored the same as the sign board and the other side being colored so as to sharply contrast with the sign board. Such an arrangement would, of course, be very complicated to operate so I provide contact panels corresponding to the letters of the alphabet for changing from one letter to another in a manner to be hereinafter described.

One embodiment of my invention is shown in the accompanying drawings, where:

Figure 1 is a plan view of the sign board showing the letter "R" outlined thereon.

Fig. 2 is a plan view of the sign board showing the same blank.

Figs. 3 and 4 are sections taken on lines 4-4 and 3-3, respectively, of Fig. 2.

Fig. 5 is a fragmentary side elevation partly in section of my invention.

Fig. 6 is a fragmentary top plan view of my invention, and

Fig. 7 is a fragmentary detail perspective of the pulley arrangement used with each shutter.

As shown in the drawing, my improved device is composed of the sign board 1 which I shall first describe generally. Upon the sign board 1 there is mounted a plurality of shutters which are arranged to conform with all the common elements in the various letters of the alphabet. There is provided the pair of elongated horizontal upper shut-

ters 2 and the small horizontal shutters 3 which lie alongside the shutters 2. Similar shutters 6 and 7 are provided upon the lower portion of the sign board. A pair of upper vertical shutters 4 and a pair of lower vertical shutters 5 are provided so as to connect approximately the extremities of the horizontal shutters 4 and a pair of lower vertical shutters 5 are provided so as to connect approximately the extremities of the horizontal shutters 2 and 6. Centrally located vertical shutters 8 and 9 extend so as to connect the middle portions of the shutters 2 and 6. Between the shutters 8 and 9 a semi-circular shutter 8' is provided. A pair of upper and lower diagonal shutters 11 and 10 are provided so as to radiate from the semi-circular shutter 8' and to terminate at the inner section of the shutters 2', extending at right angles to the vertically centrally located shutters 8. It should be understood that one side of these shutters is colored similar to the sign board whereas the other side is colored so as to contrast therewith, so that when the contrasted colored side is showing, an outline of various letters of the alphabet may be made in a manner to be hereinafter described.

By referring especially to Fig. 3 it will be noted that the shutter 5 comprises two leaves. One leaf 18 is fixedly attached to the sign board 1 by means of the screws 19 and is provided with a sleeve 16. The sleeve 16 is also provided with its leaves so that the leaves 5 and 18 may be hingedly connected to each other by means of the pins 17. In order to operate the shutter 5, there is situated thereon a staple 14 which extends from each surface so as to receive the eyes 15 which are in turn connected to the pulleys 21. One cord 20 is used to place the shutter 5 in a closed or blank position while the other cord 39 is used to swing the shutter 5 in an open or indicating position. These cords 20 and 39 pass through the apertures 13 provided in the sign board 1. Now in Fig. 4, it will be seen that the shutter 2 is also provided with a fixed leaf 18' which in turn is provided with the sleeves and a pin for hingedly mounting the shutter 2. All the shutters are operated in a similar manner, so that if the operation of one is known, the others will be clearly understood.

By referring to Sheet 2 of the drawing,

- wherein is illustrated the operating means used to move the shutters, it will be seen that the cord 39 passes over the pulley 50 which is carried upon the shaft 40 which is connected to the eye 28 of the lever 25. This lever 25 is mounted upon a fulcrum 26 and has a right angularly extending arm 27 extending from its central position. The cord 20 extends over the pulley 21 and the 5 pulley 22 which is mounted upon the shaft 41 and is inserted through the lower eye 28 and fixedly attached to the lower end of the lever 25 in any suitable manner. An extension 29 of the cord 20 passes beyond the eye 28 and is connected to the coil 10 spring 30 which in turn is attached to a bolt 31 which passes through any suitable support 33 and is fixedly attached thereto by means of a nut.
- 15 20 A pair of drums 34 are situated upon the shafts 35 behind the lever 25 so as to be in substantially the same plane as the arm 27. A belt 38 is mounted upon the drum 34 and is provided with a plurality of contact panels 36 from which extend a plurality 25 of fingers 37 for engaging the arms 27. Each of the panels 36 will designate a letter of the alphabet and therefore will be provided with the necessary fingers 37 to engage 30 the necessary arms 27 for operating the necessary shutters to make the outline of the desired letter.

The letter which the panel represents should, of course, be placed upon the panel 35 and this panel will be brought adjacent the arms 27 so that the fingers 37 will engage the same and the drums will then be operated or rotated in any suitable manner so as to force the arms 27 to take the position shown in dotted lines in Fig. 5, whereby the lever 25 will be operated so as to pull upon the cord 39 which in turn will swing the shutter to its designating position.

When it is desired to have the sign board 45 blank, it will be readily seen that all that is necessary is to rotate the drums so as to place the fingers 37 out of engagement with the arms 27 so as to allow the coil springs 30 to return the lever 25 to its normal position.

It will be readily understood that my device 55 may be put to various uses; for example the sign may consist of a plurality of the boards 1 so as to form words of any length and it will also be seen that the drums 34 may be operated so that different words 60 may be shown upon the whole board consisting of a plurality of the sign boards 1, if so desired, by arranging the panels 36 upon the belt 38.

From the foregoing description, taken in connection with the drawings, the advantages of the construction and the method of operation will be readily apparent to 65 those skilled in the art to which this in-

vention pertains, and while I have described the principle and operation of the invention, together with the device which I now consider to be the best embodiment thereof, I desire to have it understood that the device 70 shown is merely illustrative and that such changes may be made as are within the scope of the appended claims.

Having thus fully described my invention, what I claim as new and desire to secure by Letters Patent is:—

1. A device of the class described comprising a board, shutters hingedly mounted upon said board, one side of said shutters being colored similar to said board and the other side of said shutters being colored so as to contrast with said board, said shutters having such relative location upon the board that a plurality of unitary designs may be outlined thereby, a staple passing through each of said shutters, cords attached to said staples and means for pulling said cords so as to swing said shutters in the manner specified.

2. A device of the class described comprising a board, a plurality of shutters hingedly mounted upon said board, one side of said shutters being colored similar to said board and the other side of said shutters being colored so as to contrast with said board, said shutters having such relative location upon the board that a plurality of unitary designs may be outlined therewith, cords fixedly attached to said shutters, a shaft mounted a spaced distance from said board, pulleys on said shaft for receiving said cords, and means for pulling said cords for swinging said shutters.

3. In a device of the class described, the combination with a board, a plurality of shutters hingedly mounted upon said board, one side of said shutters being colored similar to said board and the other side of said shutters being colored so as to contrast with said board, said shutters having relative location on the board so that a plurality of unitary designs may be outlined thereby, a pair of cords fixedly attached to each of said shutters, a lever situated to the rear of said board, the extremity of one of said cords attached to one extremity of said lever, and the other extremity of the other cord attached to the other extremity of said lever, and means provided for operating said levers so as to pull said cords.

4. In a device of the class described, the combination with a board having a plurality of shutters hingedly mounted thereon, one side of said shutters being colored similar to said board and the other side of said shutters being colored so as to contrast with said board, said shutters having such relative location that a plurality of unitary designs may be outlined thereby, a pair of cords fixedly attached to each of said shut- 130

ters, a lever having an arm extending at right angles therefrom, one terminal of said cord attached to one extremity of said lever and the terminal of the other cord attached 5 to the other extremity of said lever, and means provided for engaging the arm of said lever so as to pull said cord.

5. In a device of the class described, the combination with a board, a plurality of 10 shutters hingedly mounted thereon, one side of said shutters being colored similar to said board and the other side of said shutters being colored so as to contrast with said board, said shutters having such relative 15 location that a plurality of unitary designs may be outlined thereby, a pair of cords fixedly attached to each shutter, said cords passing through apertures provided in said board, pulleys situated behind said board 20 for receiving said cords, and means provided for pulling said cords so as to swing said shutters.

6. In a device of the class described, the combination with a sign board having a 25 plurality of shutters hingedly mounted thereon, one side of said shutters being colored similar to said board and the other side of said shutters being colored so as to contrast with said board, said shutters having such relative locations that a plurality 30 of unitary designs may be outlined thereby, a pair of cords fixedly attached to each of said shutters and passing through apertures provided in said board, a plurality of levers 35 provided for receiving said cords, one terminal of said cords fixedly attached to one extremity of said levers, the terminal of

the other cord fixedly attached to the other other extremity of said levers, and means provided for operating said levers. 40

7. In a device of the class described, the combination with a sign board, a plurality of shutters hingedly mounted upon said sign board, one side of said shutters being colored similar to said board and the other 45 side of said shutters being colored so as to contrast with said board, said shutters having such relative locations that a plurality of unitary designs may be outlined thereby, a pair of cords fixedly attached to each 50 of said shutters, a plurality of pulleys adapted to receive said cords, a plurality of levers, the terminal of one of said cords fixedly attached to one extremity of one of said levers, the terminal of the other of 55 said cords attached to the other extremity of said levers, means provided for holding said levers in a position so that said panel will swing so that the side colored similar to said sign board will be in visible position, an 60 arm extending from each of said levers, a pair of drums, a belt passing over said drums, panels situated upon said belt, and fingers extending from said panels so as to contact with the arms of said levers for 65 operating certain of said shutters in the manner specified.

In testimony whereof I affix my signature in presence of two witnesses.

THEODOR O. JORGENSEN.
